WINDOW-SHADE SUPPORT

Application filed October 8, 1927. Serial No. 224,922.

This invention relates to an improved support for window blinds or shades, and it has reference to a structure of this kind which is readily adjustable to accommodate window 5 frames of varying widths.

The outstanding object is to provide a novel adjustable structure which may be mounted in place on the window frame without marring the polished surfaces of the 10 wood-work and without necessitating the use of screws, or other fastenings.

Briefly, the invention comprises a structure of this kind which is made up principally of two sections connected together by 15 means of a coupling which includes a novel take-up device for permitting firm clamping of the structure upon the window frame.

Other structural features and advantages 20 will become apparent from the following description and drawings.

In the accompanying drawings forming a part of this application and in which like numerals are employed to designate like parts throughout the same:

25 Figure 1 is a fragmentary front elevation of a window equipped with the support and showing the shades supported thereon,

Fig. 2 is a front elevation of the complete structure.

30 Fig. 3 is a top plan view of the same,

Fig. 4 is a view like Fig. 2 looking at the opposite side of same,

Fig. 5 is an enlarged detail view of the novel take-up device,

35 Fig. 6 is a horizontal section taken on the plane of the line 6—6 of Fig. 5,

Fig. 7 is a detail perspective view of one end portion of one of the sections of the device,

40 Fig. 8 is a perspective view of one of the slidable shade brackets.

Directing attention first to Figs. 2 and 3, it will be seen that the support is made up of two relatively movable sections, 1 and 2. As plainly shown in Fig. 7, the section 1 is in reality made up of two parts, 3 and 4. The part 3 is provided along opposite edges with longitudinally spaced recesses 5 and at one end with a hook 6. The part 4 overlaps the 50 part 3 and is provided on its longitudinal

edges with right-angularly bent tongues 7 adapted to fit into the seats 5. A pair of looped-straps 8 surround the overlapping portion of the parts 3 and 4 and hold them in adjusted position.

The section 2 comprises a relatively long strip of metal 9 which is bent intermediate its ends as to 10. Secured to this strip adjacent the bend is a short strip 11 arranged in spaced parallelism as shown in order to accommodate a longitudinally movable link 12 of the take-up device. At this time we would direct attention to Fig. 5 wherein it will be seen that this link has a slot 13 in one end to receive the aforesaid hook 6. The opposite end is formed with a circular opening to receive a correspondingly shaped disk 14 carried by and fixed immovably to a pivotally mounted operating lever 15 for movement therewith which lever 15 is interposed between the link 12 and the extended end portion of the strip 9. In this connection it will be noted that the pivotal connection 16 is eccentrically disposed. With this arrangement it will be seen that when the hooked end of the part 3 is arranged in overlapping slidable relation with the extended end portion of the strip 9 as indicated plainly in Figs. 3 and 6, a movement of the lever 15 in a direction from left to right will exert an endwise pull upon the link 12, thus holding the two sections 1 and 2 of the device together. On the opposite ends of the sections are right-angular brackets 17 to engage the window frame so that the operation just explained will effect a clamping action. It will be noted that felt pads 18 which are employed wherever necessary bear against the polished surface of the woodwork and prevent marring of the same under any unusual clamping action.

In practice the end brackets 17 are hooked over the window frame as represented in Figure 1. Then the shade is attached thereto through the medium of the slidable bracket 19. By referring to Fig. 8 it will be seen that each bracket comprises a single strip of metal having a body portion apertured at one end, while adjacent its opposite end said body portion is bent at right angles to provide a laterally extending portion which in turn is

- bent upwardly and upon itself and then bent again as at 22 to provide the right angularly disposed portion 21 extending in parallelism to the portion 20 thus forming a hook ent-
5 gaging the support as shown in Figure 3 with the apertured body portion extending later-
ly or at angles to the support. The reference character 23 simply designates a piece of felt. Of course, the length of the section 1 is ad-
10 justed by placing the tongues 7-7 in the re-
cesses 5. This permits a section to be made of any length desired so that the device may be adjusted to accommodate various widths of windows. After the device is placed upon
15 the window frame, the clamping and adjust-
ing device comprising the operating lever 15 and the eccentrically pivoted disk 14 is oper-
ated to bind the clamping bracket 17 against
the window frame.
20 It is believed that by considering the de-
scription in connection with the drawings, a
clear understanding of the construction and
use and operation of the invention will be
had. Therefore, a more lengthy description
25 is thought unnecessary.

We claim:—

1. In a window shade support of the class described, a pair of complemental sections each of which is provided at its outer end with
30 means for engaging a window frame, the in-
inner end portions of the sections being slid-
ably disposed in overlapping relationship, one of said sections being composed of rel-
atively adjustable parts, one part having lon-
35 gitudinally spaced keeper seats formed along
the marginal edges, said one part also having
a hook formed in its inner end for engage-
ment with the other of said complemental sec-
tions, and the other of the parts of said first
40 mentioned sections having bent tongues for
reception in said seats, the other of said sec-
tions being provided with a longitudinally
movable link, said link being provided with
an opening engageable with said hook, where-
45 by when said link is moved longitudinally
said sections will be adjusted one upon the
other.
2. In a window shade support of the class described, a pair of complemental sections
50 each of which is provided at its outer end with
means for engaging a window frame, the in-
ner end portions of the sections being dis-
posed in slideable overlapping relationship, one of said sections having spaced members
55 at its inner end, the outer section being com-
posed of relatively adjustable parts, a hook
formed on the inner end of one of said ad-
justable parts, and a link provided with an
opening for the reception of said hook, said
60 link being disposed between the said spaced
members, said link being further provided
with an opening of circular formation, and a
lever pivotally connected in an eccentric man-
ner to said members and a disk carried by the

lever located within the circular opening of
the link.

In testimony whereof we affix our signa-
tures.

WILLIAM C. WOFFORD.
AUGUST SODERLAND.
JOHN McBREARTY.
